INVENTOR:
ANTONIN SPERL,
BY
Graham & Dunn
ATTORNEYS.

UNITED STATES PATENT OFFICE.

ANTONIN SPERL, OF POMONA, CALIFORNIA.

FIRE ESCAPE.

Application filed January 30, 1922. Serial No. 532,600.

To all whom it may concern:

Be it known that I, ANTONIN SPERL, a citizen of the United States, residing at Pomona, in the county of Los Angeles, State 5 of California, have invented a new and useful Fire Escape, of which the following is a specification.

My invention relates to fire escapes, particularly to a fire escape which provides actual communication with the ground to persons desiring to descend from the upper floors of the building upon which the fire escape is secured, but which fire escape cannot be used for ascent unless the element 10 thereof connecting between the ground and the lower platform has first been suitably operated from above.

Although it is considered highly desirable to provide fire escapes with a means communicating with the ground so that a burning building could be quickly evacuated, the use of such ground communications has not been commonly practised owing to the easy access to the upper floors provided by these 15 devices, thus presenting an invitation to undesirable characters and exposing the property to their depredations.

It is an object of my invention to provide a fire escape having a collapsible ladder communicating with the ground which may be locked in collapsed position, in which position it presents a poor means of ascent.

It is a further object to provide such a fire escape with an obstruction adapted to 20 prevent any person who has succeeded in climbing the collapsed ladder from getting further than the underside of the platform.

It is also an object of my invention to provide an operating device associated with 25 the collapsible ladder and the obstruction which may be quickly and easily unlocked and operated by a person upon the platform of the fire escape, but which cannot be unlocked and operated from below.

It is a still further object of my invention to provide a collapsible ladder which may be rigidly, yet economically, constructed and which may be utilized with absolute safety, and be of neat appearance when collapsed.

Other objects and advantages will be made hereinafter.

Referring to the drawing which is for illustrative purposes only,

Fig. 1 is a sectional elevational view of 55 a form of my invention showing the parts thereof disposed to provide communication between the platform and the ground, being taken substantially upon a plane represented by the line 1—1 of Fig. 2. 60

Fig. 2 is a plan view of the structure shown in Fig. 1.

Fig. 3 is an elevational sectional view showing a portion of the ladder collapsed.

Fig. 4 is a section taken on a plane represented by the line 4—4 of Fig. 1. 65

In the embodiment of my invention shown in the drawing, a platform or balcony 11, provided with a railing 12, is mounted upon the side of a building in such a manner that 70 access may be had thereto through an exit 13 or by other means common to the installation of fire escapes. At one side of the platform 12 is an opening 18 provided with a door 19. From the vertical flange of the 75 angle member 20 of the opening 18 there downwardly extends an angle member 21 which rests upon and is secured to the sidewalk 22, as indicated at 23 in Fig. 1. This angle member 21 is placed near the wall of 80 the building and is disposed with one leg parallel to the face of the building and the other leg extending perpendicularly outwardly therefrom, as shown in Fig. 4.

Spaced away from the angle member 21 85 in the direction of the outer edge of the angle member 24 is placed an angle member 26 in a position inverted from that of the angle member 21. Between the angle members 21 and 26 are a series of evenly 90 spaced rungs 27 pivotally mounted as at 28. Pivoted at 30 to the frame work of the platform 11 is an operating lever 31 having an arm 32 extending therefrom which pivotally connects at 33 to the upper end of the angle member 26. A plate 35 mounted upon the upper side and at the inner edge of the door 19 carries a bell crank 36 which is linked to the platform by a member 37 and to the lever 31 by a member 38. 95

By moving the handle 39 of the lever 31 in the direction indicated by the arrow 40 in Fig. 1, an upward movement of the arm 32 in the direction of the arrow 41 is accom-

plished which lifts the angle member 26 from the sidewalk 22 and causes it to swing upwardly in a circular direction toward the angle member 21 owing to the presence of 5 the rungs 27 which are linked between the two angle members. Coincident with the lever 31 reaching the position in which it is shown in Fig. 3, a position of the angle member 26 against the angle member 21 is 10 assumed, as shown in this figure, and the door 19, owing to the manner in which it is associated in movement with the lever 31 through the link member 38 and the members 36 and 37, is swung around hinge 42 15 into the closed position shown also in Fig. 3.

Upon the angle member 21 are a number of latch hooks 45 adapted to engage plates 46 upon the angle member 26. These latches are operated by a vertical rod 47 20 which is attached at its upper end 48 to a bell crank 49. Between the end 52 of the bell crank 49 and a locking lever 53 there connects a link member 54. When the lever 31 has been lowered from the position shown 25 in Fig. 1 to the position shown in Fig. 3 to collapse the ladder formed by the angle members 21 and 26 and the rungs 27, the locking lever 53 is swung upwardly around the pivot 56 causing a hook 57 formed there- 30 upon to come to rest over a pin 58 extending from the lever 31. With the lifting of the lever 53, the upper end 52 of the bell crank 49, through the connection of the lever 53 therewith through the link 54 and the rod 35 47, is moved correspondingly downwardly and the latches 45 are brought into position over the inwardly extended ends of the plates 46, as shown at 60 in Fig. 3, thus locking the angle member 26 securely 40 against the angle member 21.

It will be perceived that when the angle members 26 and 21 are locked together, a formation is presented which is very difficult to climb and that, in the event a person is successful in climbing the collapsed 45 ladder, the closed door 19 obstructs passage further than the underside of the platform 11. The door 19 may be so fitted that the opening 18 will be nearly entirely filled so that but little grip will be presented for the fingers; thus it would only be possible for one of considerable athletic attainment to mount the platform after having climbed the closed angle members 21 and 26.

My device may be easily operated by a 55 person upon the platform as little effort is required to lift the lever 31 owing to the fact that there is a natural tendency for the angle member 26 to drop into the down 60 position after the upper end thereof has been thrown off the dead center, and it is entirely impossible for the device to be operated from below as the locking lever is situated centrally and to the rear of the platform, as will be perceived, and is protected

by the floor 65 from being actuated by any one below the platform.

I claim as my invention:

1. In a fire escape, the combination of: a platform having an opening through the 70 floor thereof; means providing access to said fire escape from the interior of a building; a collapsible ladder extending downwardly from said opening; a door hinged to said platform at the edge of said opening; a 75 lever hinged upon said platform for collapsing said ladder; and link means acting, between said lever and said door, to close said door when said lever is actuated to collapse said ladder.

2. In a fire escape, the combination of: a platform having an opening in the floor thereof; a vertical member extending downwardly from said platform substantially at the edge of said opening, said member being rigidly supported; a second vertical member suitably spaced from said rigid vertical member; ladder rungs pivoted between said vertical members; a door for closing said opening hinged upon said platform; an operating lever, hinged upon said platform and pivoted to said second vertical member, for lifting said second member into a position against said rigid member; and link members associated with said operating 95 lever for closing said opening with said door when said operating lever is actuated to bring said vertical members together.

3. In a fire escape, the combination of: a platform having an opening in the floor 100 thereof; a vertical member extending downwardly from said platform substantially at the edge of said opening, said member being rigidly supported; a second vertical member suitably spaced from said rigid vertical member; ladder rungs pivoted between said vertical members; a door for closing said opening hinged upon said platform; an operating lever, hinged upon said platform and pivoted to said second vertical member, 105 for lifting said second member into a position against said rigid member; and link members associated with said operating lever for closing said opening with said door when said operating lever is actuated to bring said vertical members together; and means for locking said operating lever in actuated position.

4. In a fire escape, the combination of: a platform having an opening in the floor 110 thereof; a vertical member extending downwardly from said platform substantially at the edge of said opening, said member being rigidly supported; a second vertical member suitably spaced from said rigid vertical member; ladder rungs pivoted between said vertical members; a door for closing said opening hinged upon said platform; an operating lever, hinged upon said platform and pivoted to said second vertical member, 115 for closing said opening with said door when said operating lever is actuated to bring said vertical members together; and means for locking said operating lever in actuated position.

lifting said second member into a position against said rigid member; link members associated with said operating lever for closing said opening with said door when said operating lever is actuated to bring said vertical members together; and means for locking said operating lever in actuated posi-

tion and for locking said second vertical member against said rigid vertical member.

In testimony whereof, I have hereunto set 10 my hand at Pomona, California, this 21 day of January, 1922.

ANTONIN SPERL.
